UNITED STATES PATENT OFFICE.

WILLIAM B. BURGET, OF KANSAS CITY, MISSOURI.

MUSICAL WHISTLE.

1,250,557.

Specification of Letters Patent. Patented Dec. 18, 1917.

Application filed March 10, 1917. Serial No. 153,956.

To all whom it may concern:

Be it known that I, WILLIAM B. BURGET, a citizen of the United States of America, residing at Kansas City, in the county of 5 Jackson and State of Missouri, have invented certain new and useful Improvements in Musical Whistles, of which the following is a specification, reference being had therein to the accompanying drawing.

10 This invention relates to a musical whistle and has for its principal object the production of a device wherein the horn of the whistle is provided with a simple and efficient means for releasably holding the 15 mouth-piece in engagement therewith.

Another object of this invention is the production of a musical whistle wherein the horn of the device is provided with a plate having a number of flanges thereon so as to 20 allow the plate to receive a portion of the mouth-piece and hold the same by means of the flanges, thereby releasably holding the mouth-piece upon the horn.

A still further object of this invention is 25 the production of a musical whistle wherein the mouth piece is provided with an extension for permitting the mouth-piece to be attached to the horn, and by which the mouth piece may be held when being played independently of the horn.

With these and other objects in view this invention consists of certain novel combinations, constructions, and arrangements of parts as will be hereinafter fully described 30 and claimed.

In the drawings:

Figure 1 is a top plan view of the musical whistle.

Fig. 2 is a bottom plan view of the musical 40 whistle.

Fig. 3 is a central longitudinal section through the musical whistle.

Fig. 4 is a section taken on the line 4—4 of Fig. 3, looking in the direction of the 45 arrows.

Fig. 5 is a plan view of the blank from which the horn is formed, showing the plate carried thereby.

Fig. 6 is a top plan view of the mouth 50 piece.

Fig. 7 is a bottom plan view of the mouth piece.

Fig. 8 is a side elevation of the mouth piece.

55 Fig. 9 is a top plan view of a slightly modified form of the mouth piece.

Fig. 10 is a bottom plan view of the modified device, as shown in Fig. 9.

Fig. 11 is a side elevation of the modified 60 form of the mouth piece.

Referring to the accompanying drawings by numerals, it will be seen that the horn is formed from a blank and comprises a body 1. This body 1 is rolled in a substantially cylindrical manner, as illustrated 65 clearly in Figs. 1, 2, and 3, and is joined together by solder or like means so as to have the stem 2 thereof upon its lower portion. The bell 3 is also formed from a blank and is rolled so as to have the stem 4 thereof in 70 alinement with the stem 2 of the body 1 and this bell 3 fits upon the outer end of the horn body 1, as shown clearly in Fig. 3. The body 1 although cylindrical at its outer 75 end is flattened in cross-section at its inner end so as to form a substantially rectangular structure in cross-section, as shown clearly in Fig. 4.

The retaining plate 5 is positioned within the body 1 when the horn is assembled and 80 is retained in position by means of an inwardly bent flange 6 soldered thereto, or otherwise secured, as shown in Figs. 3 and 5. The plate 5 is provided with overhanging 85 side flanges 7 and an overhanging inner flange 8. By referring particularly to Fig. 3 it will be seen that the plate 5 is spaced from the inner portions of the body 1 of the horn so as to extend evenly throughout its entire length for releasably retaining the 90 mouth piece of the horn in a set position.

The mouth piece of the whistle comprises a top section 9 and a lower section 10. Since the mouth piece is formed from a blank sheet of material and is bent intermediate 95 its ends it will be seen that the sections 9 and 10 are carried in spaced relation, as shown in Fig. 8. It should further be noted that the upper section 9 projects for a considerable distance beyond the lower section 100 10. These sections 9 and 10 are provided with reduced alined openings 11 formed therein adjacent the junction 12 of the sections 9 and 10.

The grooves 13 are formed in alinement 105 with each other and are struck inwardly upon the sections 9 and 10 at a greater distance from the junction 12 of the sections 9 and 10 than are the openings 11. When this mouth piece is played the grooves 13 are intended 110 to constitute guides for the lips of the player, while the mouth piece may be held

by the projecting section 9 which is connected to the top of the mouth piece. At this time it is obvious that the section 10 will be free to spring back and forth, if so desired, 5 in order to facilitate the playing of high or low notes.

For using the mouth piece upon a horn the section 9 because of its projecting end is passed into the horn and bears upon the 10 plate 5, being held against side displacement and in a straight line by means of the gripping overhanging flanges 7 and 8. Since the inner ends of the body 1 of the horn are circularly notched, as shown at 14, sufficient 15 space is provided for the reception of the lower section 10 without binding or holding the lower section 10 of the mouth piece. As a consequence, the mouth piece may be easily 20 played in the usual manner, being held in engagement with the body of the horn by means of the plate 5 and the flanges thereof.

By referring to Figs. 9 to 11 inclusive a slightly modified form of the mouth piece is disclosed which is intended to produce 25 more of a flute like note than the preferred mouth piece, for in the preferred mouth-piece a note similar to a clarionet is intended to be made. In this modified form of the mouth piece the sections 15 and 16 are joined 30 as indicated at 17 and the section 15 projects for a considerable distance beyond the section 16. Instead of having the depressed grooves as in the preferred form the sections 15 and 16 are provided with outwardly 35 struck lips 18 in alignment with each other, while between the lips and the portions 17 are formed aligned openings 19. Because of the construction of the device as shown in Figs. 9 and 11 inclusive, a lightly modified 40 tone or note will be disclosed over the form of mouth piece shown in Figs. 6 to 8 inclusive.

From the foregoing description it will be seen that a very simple and efficient musical 45 whistle has been provided, wherein the horn body is provided with a plate having overhanging gripping flanges for releasably holding the mouth piece in releasable engagement therewith, while the mouth piece 50 is provided with a projection for engaging the plate and flanges, and, furthermore, the mouth piece is provided with grooves and openings for facilitating the formation of notes, which being played into the horn will 55 produce a greater volume, and which can be easily changed by the springing of one sec-

tion of the mouth piece or by the muffling of the horn.

What is claimed is:—

1. In a device of the class described, the combination of a horn body, a plate carried by said body, a flat mouth piece, said flat mouth piece engaging said plate, and means formed upon said plate and engaging said mouth piece for holding the same in releasable engagement with said plate. 60

2. In a device of the class described, the combination of a horn body, a plate carried upon said body, overhanging flanges formed upon said plate, a flat mouth piece fitting upon said plate, and said flanges gripping said mouth piece for releasably holding the same in engagement with said plate. 70

3. In a device of the class described, the combination of a horn body having a bell thereon, an inwardly extending flange formed upon said horn body, a plate fitting upon said flange, means for holding said plate in engagement with said flange, overhanging side and forward flanges formed upon said plate, said mouth piece comprising a pair of spaced sections, one of said sections projecting beyond the remaining section, said projecting section fitting upon said plate and being gripped by said flanges, 80 whereby said mouth piece will be releasably held in engagement with said horn body. 85

4. In a device of the class described, the combination of a horn body, said horn body being formed from a blank and being rolled to form a cylindrical outer end and a comparatively flat inner end, an inwardly extending flange formed upon said inner end of said horn body, a plate engaging said flange, said plate having side flanges formed thereon, said body having a circularly notched lower portion at the inner end thereof, a mouth piece comprising a pair of sections having grooves and openings formed therein, one of the sections of said mouth piece projecting beyond the remaining section, the projecting section fitting upon said plate and being gripped by said flanges, whereby said mouth piece will be releasably held upon said horn so as to allow the notes 100 thereof to pass into the horn, while the other section of said mouth piece will be free to move because of the notching of said horn body. 105

In testimony whereof I hereunto affix my 110 signature.

WILLIAM B. BURGET.
